NONREFILLABLE BOTTLE

John R. Marshall, Yorkville, Ill.

Application February 4, 1935, Serial No. 4,894

4 Claims. (Cl. 215—15)

This invention relates to that class of containers generally referred to in the trade and art as non-refillable bottles, and it has specific reference to a type of bottle or flask which is particularly designed and adapted for the sale of alcoholic beverages.

Needless to say, I am aware of the fact that various types of bottles have been expressly constructed to accomplish the result sought after here. It is my primary aim, therefore, to generally improve upon known marketed and patented bottles of the non-refillable variety by providing one characterized by refinements and improvements calculated to expedite initial filling and to thereafter guard against filling of the used bottle with spurious and imitation liquor.

It goes without saying that the market is burdened with fictitious and substitute products sold by irresponsible persons as representing certain genuine and trade-marked products. It stands to reason, therefore, that there is a long-felt need for the use of non-refillable bottles. At the same time, most bottles which have been constructed for the purpose are characterized by valves and other unreliable contraptions, and even when of a simple one-piece type are not susceptible of expedient use at the time of filling at the distillery or other authorized place of business.

Under the circumstances, and after considerable forethought and deliberation, I have evolved and produced a unique non-refillable bottle which, in my judgment, constitutes an innovation to this particular line of endeavor. Specifically it is believed to be a refinement due to the particular selection and coordination of features which are involved in its make-up. Specifically and structurally speaking, novelty is thought to reside in the construction of a hollow flask which includes a suitable body portion shouldered at its top and having a centralized upstanding filler and pouring neck, said body being formed on its interior with an integral divider unit including a partitioning element connecting at its upper end with the neck and extending downwardly into the body and joined thereto at the juncture of the body with the bottom to define individual compartments, this divider unit being provided adjacent the bottom with an aperture constituting the sole means of communication between the two compartments.

Other features and advantages will become more readily apparent from the following description and accompanying illustrative drawings.

In the drawing wherein like numerals are employed to designate corresponding parts throughout the views:

Figure 1 is a substantially central vertical sectional view through a non-refillable bottle constructed in accordance with the principles of the present inventive conception.

Figure 2 is a similar central vertical section which may be described as transverse in character and taken at substantial right angles to Figure 1.

In reducing the invention to practice, I have found it expedient and practicable to employ a one-piece all glass bottle. In practice, this bottle may be of any appropriate external configuration. Moreover, it may be of suitable size and cross sectional shape, that is in the form of a flask for pocket use, or cylindrical, oval or other cross sectional form. The body portion of the bottle, indicated by the numeral 5 serves as the container proper and in conjunction with the other features defines the main liquid compartment 6. The neck of the bottle, which is in the form of a protruding beaded nipple is indicated at 7. Then on the shoulder of the bottle adjacent to the neck is a vent hole or orifice 8 having a cooperative extension 9 which may be conveniently distinguished as a venting teat.

In addition to the means 8 and 9, the essential feature of distinction on which novelty is predicated exists in the adoption and use of the special adapter means on the interior of the bottle. In molding or forming the bottle, this part 10 is in effect a continuation of the neck 7, that is to say, it is in registry at its upper and narrower end with the external neck 7 and it then flares down gradually where it meets and merges into the bottom or base of the bottle. In so doing, it defines an inner compartment 11. The opposed flared ends 12 diverge in a direction toward the vertical ends 13 of the bottle and join the bottom at point 14 adjacent the juncture between said ends 13 and the bottom 15. The remaining end portions 16 of the internal neck flare outwardly in diverging directions and join to the bottom as indicated at 17, at which point the front and back portions 18 join the base 15. Thus, in effect, I provide a double flaring bell whose proportions are substantially commensurate to and join the perimeter portion of the bottom 15. Or stated otherwise, the open bottom of the bell-like neck has an area substantially equal to that of the bottom 15. The liquid passes from the inner compartment 11 to the outer compartment 6 by 55

way of a passage 19. Incidentally there may be one or more of these passages to expedite flow of the liquid.

In practice, the bottle is filled through the companion external and internal necks 7 and 10. The gradual taper of the neck, as a unit, expedites this particular operation and allows an almost continuous feed from the neck or compartment 11 into the outer compartment 6. As the column of liquid fills up into the compartment 6, the pocketed air is relieved by way of the vent means 8 and 9. When the bottle is filled, the vent opening is sealed by fusing the glass in an obvious manner.

15 An attempt to refill the bottle will result in but part of the "gland" 6 being filled, the trapped air pressure holding the level of the liquid so far below the full level that a prospective purchaser of an imitation liquid would realize that substitution had been made.

20 The bottle could be improperly filled by unauthorized persons either by filling in a vacuum chamber or by manipulating a tube through the orifice 19 and up to the top of the bottle to allow the air to escape. Such attempts would be too slow in the second instance and too costly in the first instance to be carried on in a wholesale manner. By laying the bottle on its side it could be filled less than half way but when righted the air would trap itself in the upper portion successfully preventing complete filling. The tip on top could not be resealed if broken to refill.

25 It is believed by the inventor that such a bottle is desired by distillers and medicine companies whose bottles might be refilled by inferior products and sold at original price impairing the real producer of reputation and faith in the product.

30 It is thought that persons skilled in the art to which the invention relates will be able to obtain a clear understanding of the invention after considering the description in connection with the drawing. Therefore, a more lengthy description is regarded as unnecessary.

35 40 45 Minor changes in shape, size and rearrangement of details coming within the field of invention claimed may be resorted to in actual practice, if desired.

Having thus described the invention, what is claimed as new is:

1. A non-refillable bottle comprising a hollow body formed with a filling and pouring neck and provided on its interior with a tubular member in registry at its intake end with and joined to said neck, said tubular member having its lower portion gradually tapered and flared in diverging directions and attached to the perimeter of the bottom of the bottle at which point it is provided with a passage. 5

2. A non-refillable bottle comprising a hollow body formed with a filling and pouring neck and provided on its interior with a tubular member in registry at its intake end with and joined to said neck, said tubular member having its lower portion gradually tapered and flared in diverging directions and attached to the perimeter of the bottom of the bottle at which point it is provided with a passage, and said bottle having a fusible vent for permanent closing. 15

3. A non-refillable bottle comprising a hollow flask including a substantially flat bottom and a shouldered upper end portion having a centralized upstanding filler and pouring neck and an internal inverted bell-shaped filling and safeguarding funnel having the lower ends of its walls joined integrally with the perimeter of said bottom and its lower portion apertured and its body portion rising perpendicularly to the full height of the 25 flask, the upper end thereof matching and merging smoothly into said neck to provide the desired flush unobstructed continuity of construction and action. 30

4. A non-refillable bottle comprising a hollow flask including a body portion shouldered at its top and having a centralized upstanding filler and pouring neck, said body being formed on its interior with an integral divider unit including a partitioning element registering at its upper 40 end with said neck and extending downwardly into the body and joined thereto at the juncture of the body with the bottom to define individual compartments, said divider unit being provided adjacent the bottom with an aperture constituting the sole means of communication between said compartments. 45
